[57] CLAIM

The ornamental design for a combination planar molder, as shown and described.

DESCRIPTION

FIG. 1 is a front elevational view of a combination planar molder showing our new design;

FIG. 2 is a side elevational view taken from the right of FIG. 1;

FIG. 3 is a top plan view thereof, the bottom being unornamented;

FIG. 4 is a side elevational view taken from the left of FIG. 1;

FIG. 5 is a rear elevational view thereof.
